US0D1099898S

(12) **United States Design Patent** (10) **Patent No.:** **US D1,099,898 S**
(45) **Date of Patent:** **** Oct. 28, 2025**

(54) **DISPLAY**

(71) Applicant: **SONY GROUP CORPORATION**,
Tokyo (JP)

(72) Inventor: **Naoe Imafuku**, Tokyo (JP)

(73) Assignee: **SONY GROUP CORPORATION**,
Tokyo (JP)

(**) Term: **15 Years**

(21) Appl. No.: **29/878,495**

(22) Filed: **Jun. 22, 2023**

(30) **Foreign Application Priority Data**

Dec. 28, 2022 (JP) ..... 2022-028163 D

(51) **LOC (15) Cl.** **14-02**

(52) **U.S. Cl.**

USPC **D14/126**; D14/371

(57) **CLAIM**

The ornamental design for a display as shown.

DESCRIPTION

FIG. 1 is a front, top, right perspective view of a display showing my new design;

FIG. 2 is a rear, top, right perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a top plan view thereof.

1 Claim, 7 Drawing Sheets
